FIG. 1.

FIG. 2

Frank S. Crowell, Inventor
By His Attorneys, Doisier & Rice

UNITED STATES PATENT OFFICE.

FRANK S. CROWELL, OF TOLEDO, OHIO, ASSIGNOR TO THE EDWARD N. RIDDLE CO., OF TOLEDO, OHIO, A CORPORATION OF OHIO.

DESIGN FOR A LAMP.

59,197.

Specification for Design.

Patented Oct. 4, 1921.

Application filed January 12, 1921. Serial No. 436,841. Term of patent 7 years.

To all whom it may concern:

Be it known that I, FRANK S. CROWELL, a citizen of the United States, residing at Toledo, in the county of Lucas and State of Ohio, have invented a certain new, and original, and ornamental Design for a Lamp, of which the following is a specification, reference being had to the accompanying drawing, forming part hereof.

Fig. 2 is a top plan view of the base, looking downwardly.

I claim:

The ornamental design for a lamp, as shown.

FRANK S. CROWELL.
